UNITED STATES PATENT OFFICE.

JOHN E. DONOVAN, OF CINCINNATI, OHIO.

SPLIT PULLEY.

SPECIFICATION forming part of Letters Patent No. 593,646, dated November 16, 1897.

Original application filed April 17, 1895, Serial No. 546,161. Divided and this application filed April 26, 1897. Serial No. 633,840. (No model.)

To all whom it may concern:

Be it known that I, JOHN E. DONOVAN, of Cincinnati, Hamilton county, Ohio, have invented certain new and useful Improvements 5 in Split Pulleys, of which the following is a specification.

This application is a division of my application, Serial No. 546,161, filed April 17, 1895.

This invention pertains to improvements 10 in split pulleys, and the same will be readily understood from the following description, taken in connection with the accompanying drawings, in which—

Figure 1 is a face elevation of a split pulley exemplifying my invention; Fig. 2, a perspective view of one of the halves of the pulley; Fig. 3, a side elevation of one of the bushings; Fig. 4, a perspective view of the pair of bushings belonging in a single pulley, one 20 half of one of these bushings being, however, omitted and the two halves of the other bushing being shown as abnormally separated; and Fig. 5, a vertical transverse section of one of the bushings in conjunction with a 25 shaft.

In the drawings, 1 indicates the rim of the pulley; 2, the hub; 3, the joint-cracks between the two halves of the rim, the rim being cast integrally and subsequently broken in two; 30 4, a pair of ribs extending across the inner face of the rim at each of the joint-cracks, these ribs forming between them a V-shaped groove whose root is in the plane of the joint-crack; 5, lugs projecting inwardly from the rim of the pulley, there being eight of these lugs arranged in pairs, a pair near each edge of the rim and straddling the joint-cracks, the lugs standing some distance apart; 6, bolts passing through the pairs of lugs and 35 serving to unite the pulley-halves at the rim; 7, bosses formed upon the inner faces of lugs 5 and surrounding the bolts 6, these bosses being coned to form an angular groove where they make contact with each other, it being 40 understood that the two bosses of each pair are cast integrally and subsequently cracked when the pulley is to be parted; 8, bolting-lugs projecting outwardly from the periphery of the hub and disposed in pairs, one pair at 45 each end of the hub and straddling the joint-cracks therein, it being understood that the

hub, as well as the rim, is split; 9, a longitudinal groove in each side of the exterior of the hub in the plane of the joint-cracks in the hub, these grooves extending as apertures 55 through the web at the root of the pulley-arms, these grooves therefore cutting largely through the wall of the hub and leaving standing only thin interior portions at the bore of the hub, small portions being left standing at 60 the outer portion of the roots of the arms, these grooves being cored so deeply, except at the extreme ends of the hub, that when the hub is bored the grooves result in slots in the hub, except at the ends of the hub; 10, bolts engaging 65 holes in lugs 8 and serving as clamping-bolts for the hub; 11, the bushings, the same being much shorter than the hub of the pulley and employed in duplicate, one bushing being disposed at each end of the pulley-hub, these 70 bushings being also split; 12, exterior flanges at each end of each bushing, these flanges being accurately turned to fit the bore of the pulley, the exterior of the body of the bushing between the flanges being somewhat less 75 than the bore of the pulley; 13, slots formed through the opposite walls of the bushings and extending from near one end to near the other end of the bushing, these slots being in the 80 plane of separation of the bushing-halves and serving to divide the halves from each other, except at small end portions at the outer part of flanges 12; 14, trunnions projecting outwardly from the central portion of the periphery of the bushings, slots 13 cutting through 85 these trunnions, so that each of these complete trunnions is carried half by one half of the bushing and half by the other half of the bushing; 15, a pair of trunnions projecting radially from the body of each bushing in a plane 90 at right angles to the plane of separation of the bushing-halves; 16, an eccentric chamber forming an enlargement of the bore of one-half of each bushing; 17, a roller disposed in each chamber 16, parallel with the axis of the 95 bushing, and having such diameter as to nearly fill the space between the shaft and the bore of chamber 16, where that bore is the deepest; 18, flanges at the ends of chamber 16 in each bushing, these flanges confining 100 roller 17 endwise, but loosely, and being bored concentric with the axis of the pulley; 19, the

shaft; 20, apertures cast in the hub of the pulley to loosely receive trunnions 14 of the bushings, these apertures being in the plane of the joint-crack of the hub of the pulley and 5 formed half in each half of the hub at the joint-crack; and 21, apertures formed in the bore of the pulley to be loosely engaged by trunnions 15 of the bushings.

The improved pulley without its bushings 10 is to be integrally cast and then bored and turned, after which the pulley is to be cracked into two halves by the use of drifts or other suitable implements in the grooves 9 at the hub and in the grooves formed between the 15 ribs at the rim. The groove formed between ribs 4 nicely guides the rim crack free from the influence of lugs 5 and leaves the cracked rim-joint the full thickness of the rim. Bolts 6 and 10 are then to be applied, thus securing 20 the two halves of the pulley together with the fractured surfaces interlocking. Bolts 6 are near each edge of the rim and away from the pulley-arms and make the rim-joint tight and permanent, there being an absence of the 25 chafing usually found in split pulleys constructed on this general principle.

The pulley may, if desired, instead of being bored and turned before it is broken in two, be bored and turned after it is broken in two 30 and the halves reunited by the bolts. In either case it will be found that the bolting brings practically no distorting strains upon the pulley-rim.

If desired, the pulley may be employed as 35 a solid pulley without being broken in two, in which case its construction permits of its being broken in two at any future time when it be desired to employ the pulley as a split pulley.

40 The bushings are each cast integrally, after which they are bored and then turned at flanges 12 to accurately fit the pulley, after which they are broken in two by means of a drift inserted in slots 13. The bushings are 45 then to be disposed in the ends of the bore of the hub of the pulley, trunnions 14 lying in apertures 20 and trunnions 15 engaging apertures 21. The trunnions prevent any possible rotation of the bushings within the pulley- 50 hub, and for many conditions either pair of trunnions 14 or 15 may be omitted. As an article of manufacture it is preferable that the bushings be not broken in two until the occasion for their use arises, this plan for the 55 time being reducing the number of pieces to be dealt with. When the pulley, with its bushings, is to be applied to a shaft, the roller 17 is laid in the chamber 16 and the pulley and bushing put upon the shaft. The turning 60 of the pulley a trifle in either direction with reference to the shaft causes the roller to be pinched between the shaft and the wall of the chamber, the pulley thus being prevented from further rotation with reference 65 to the shaft and being thus securely held in place upon the shaft.

It is obvious that the pulley or the pulley

with its bushings is adapted to be secured to its shaft by any of the usual means, such as a set-screw or key. Where it is desired to 70 employ the pulley or the pulley with its bushings on a shaft upon which it is to be held by clamping friction alone, then in that case it is preferable that the contiguous surfaces at the joint-cracks of the pulley-hub and bushings should be cut away, so as to give clamping 75 clearance. When the pulley is thus used upon a shaft by which it is held by clamping friction alone, the disposition of the short bushings at the ends of the pulley-hub give 80 a certain degree of independence and elasticity to the clamping system, thus permitting the pulley to be more readily clamped to a shaft which is not truly uniform in diameter or which has become roughened or burred. 85

If the cores employed in forming grooves 9 cut through into the bore of the hub, as cast, it would be practically impossible to set the cores, it being requisite that some distance be left between the core forming the bore and 90 the core forming the grooves. Grooves 9 may therefore be bored of such depth as not to cut through to the central bore, the remaining metal being, however, so thin that when the pulley-hub is bored this thin metal will be cut 95 away, thus leaving slots in the sides of the hub extending nearly from end to end and leaving also open the apertures 20.

I claim as my invention—

1. In a split pulley, the combination, substantially as set forth, of a divided rim and hub with the uniting pulley-arms forming two pulley-halves, lugs and bolts uniting said pulley-halves, and a pair of ribs projecting inwardly from the rim at each joint-crack therein, the inner faces of said ribs being angularly disposed with reference to each other to form a V-shaped groove whose root is at the inner surface of the pulley-rim at the joint-crack, said rim having normal thickness at 100 the roots of said grooves.

2. In a split pulley, the combination, substantially as set forth, of a divided rim and hub having the rim united to the hub by arms, lugs and bolts at the hub for clamping the 105 hub-halves together, a pair of separated lugs projecting inwardly from the rim at each edge thereof near the ends of the joint-cracks in the rim, the separations between the two lugs of each pair straddling the joint-cracks of the rim, and the two pairs of lugs at each joint-crack being disconnected from each other, the rim having full normal thickness between the two pairs of lugs at each joint-crack, perforated bosses projecting inwardly from the 110 inner faces of said lugs into contact with each other, and clamp-bolts passing through said 115 lugs and perforated bosses.

3. In a split pulley, the combination, substantially as set forth, of a rim, a hub, arms uniting the hub and rim and uniting with each other by a web at the root of the arms, there being longitudinal grooves at opposite 120 sides of the hub and extending as apertures 125

through said web at the root of the arms, portions of said web forming outer walls for said apertures, and bolts and lugs for uniting the pulley-halves when the pulley is broken in two.

4. In a split pulley, the combination, substantially as set forth, of a rim, a hub, and arms uniting said hub, said hub being provided with longitudinal grooves at opposite sides and extending from end to end of the hub, the central portion of said grooves being deepened to form slots extending through the wall of the hub and into the bored hub-hole of the pulley, said grooves being shallower at the ends of the hub, and lugs and bolts at the rim and hub for uniting the pulley-halves after the pulley is broken in two.

5. In a split pulley, the combination, substantially as set forth, of a divided rim and divided cylindrically-bored hub, lugs and bolts for uniting the pulley-halves, and a bored bushing having a cylindrical body smaller than the bore of said hub and having at each end a flange concentric with the bore of the bushing and fitting within the bore of the pulley.

6. In a split pulley, the combination, substantially as set forth, of a divided rim and divided cylindrically-bored hub provided

with apertures in its wall, lugs and bolts for 30 uniting the pulley-halves, a bored bushing having its exterior cylindrical to fit the bore of the hub, and trunnions extending from the periphery of the bushing into engagement with the said apertures in the bore of the 35 pulley.

7. In a split pulley, the combination, substantially as set forth, of a divided rim and hub, lugs and bolts for uniting the pulley-halves, and a bored bushing having exterior 40 portions fitting the bore of the pulley and provided with longitudinal slots extending nearly from end to end of the bushing and through the wall of the bushing, the wall of the bushing being continuous at the unslot- 45 ted ends thereof.

8. In a pulley, the combination, substantially as set forth, of a rim, a hub provided with a bore concentric with said rim and provided at each end with a chamber eccentric 50 to said bore, and a roller disposed longitudinally within each of said chambers and adapted to engage between a shaft and the walls of said chambers.
